CLAIM

The ornamental design for a portable sauna device as shown and described.

DESCRIPTION

FIG. 1 is a top perspective view of a portable sauna device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view of the portable sauna device from FIGS. 1-7 with the door in an open configuration;

FIG. 9A is a front view of a portable sauna device showing my new design in an alternative embodiment; and,

FIG. 9B is an enlarged view of the encircled portion 9B indicated in FIG. 9A.

The broken lines depicting the remainder of the portable sauna device form no part of the claimed design.

1 Claim, 10 Drawing Sheets
